UNITED STATES PATENT OFFICE.

RICHARD S. GIESE, OF PITTSBURGH, PENNSYLVANIA.

ELECTRIC-LIGHT FIXTURE.

1,331,756.

Specification of Letters Patent. Patented Feb. 24, 1920.

Application filed February 12, 1919. Serial No. 276,617.

To all whom it may concern:

Be it known that I, RICHARD S. GIESE, a citizen of the United States, residing at Pittsburgh, in the county of Allegheny and State of Pennsylvania, have invented a new and useful Electric-Light Fixture, of which the following is a specification.

This invention has reference to electric light fixtures, and its object is to provide a combined ceiling bowl and shade attachable to the wall by a single fastening device and arranged to hold a cluster of electric lamps which may be set in and sustained by the bowl without any carrying fixture other than the bowl itself.

In accordance with the invention, the bowl is a one-piece structure of glass open only where engaging the ceiling and provided with a cluster or group of protrusions or shades each suitably shaped and proportioned to hold an electric light bulb with a socket carrying the bulb located in the bowl but unattached to any bracket or sustaining device. Centrally traversing the bowl is a pendant rod, or bar, or pipe with a nut screwed onto its lower end outside of the bowl which is traversed by the pipe so as to sustain the bowl and clamp it against the ceiling.

Provision is made for diffusing the light by producing the bowl and cluster of shades of frosted or milk glass with the bottom portions of the protrusions of clear glass so that a more intense illumination is caused immediately beneath the bowl and a soft diffusive illumination is caused by the remainder of the bowl.

Moreover, aside from a small sustaining pipe or rod centralized with respect to the bowl, no metallic parts whatever are employed, the lamps and sockets not being considered. Furthermore, by utilizing a ceiling outlet or the sustaining member, which may be a pipe, the lamps and sockets are merely loosely mounted in the shades forming pendent parts of the bowl and constituting the cluster.

The invention will be best understood from a consideration of the following detailed description taken in connection with the accompanying drawing forming part of this specification, with the understanding, however, that the invention is not confined to any strict conformity with the showing of the drawing, but may be changed and modified so long as such changes and modi-

fications mark no material departure from the salient features of the invention as expressed in the appended claims.

In the drawing:—

Figure 1 is a diametric section of the electric light fixture, with some parts in elevation.

Fig. 2 is a bottom plan view of the structure shown in Fig. 1.

Referring to the drawing, there is shown a bowl 1 which may correspond in general shape to ceiling or other bowls used in electric light fixtures, and the bowl is open at the upper end and provided with a marginal bead 2 which, in accordance with the invention, is designed to directly engage against the ceiling of a room. The bowl has a rounded bottom portion which may be of customary shape, and at intervals on the bottom portion near the sides of the bowl are pendent projections 3 which are shown as slightly tapering toward the lower ends, although this particular shape is by no means obligatory. The pendent portions 3 open directly into the interior of the bowl and constitute shades for housing electric lamp 4 which latter are provided with sockets 5 of ordinary construction. The body of the bowl and the major portion of the pendent projections 3 are formed of frosted or milk glass, or in fact any type of glass of a light-distributive nature. The bottom portion of each pendent shade 3 is of clear glass, as shown at 6, or this portion of the shade may be of any character of a nature permitting more brilliant illumination directly beneath the fixture or bowl than is provided by the remainder of the material of which the bowl is made. The entire bowl including the pendent projections is of one-piece construction, and while the bowl may be as ornamental as desired, it may be formed of, so far as its light diffusive characteristics are concerned, one character throughout, except at the bottoms of the pendent projections where the arrangement is such that there is neither material impediment to nor diffusion of light.

Secured to the ceiling of the room in which the fixture is to be installed, is a pendent rod 7 which may be either a solid rod or a pipe, and the bowl 1 has a centralized opening 8 through which the rod or pipe 7 projects and, where projecting, the pipe or rod 7 has an exteriorly threaded portion 9. Applied to the threaded portion

9 is a nut or knob 10 which may be of any suitable ornamental form engaging and sustaining the bowl and holding the bead 2 against the ceiling of the room with sufficient firmness to prevent displacement of the bowl.

The sockets 5 have electric conductors 11 attached thereto, and these conductors may lead to a suitable ceiling outlet, or may enter the pendent holding member 7 for the bowl where such member is in the form of a pipe, the conductors being ultimately carried through the pipe and connected to a supply of current.

15 The bowl before application to the ceiling has the lamps 4 placed therein with each lamp in a respective one of the pendent shades 3, which latter may be arranged in a symmetrical cluster as indicated in the drawing or in any suitable manner, and this bowl with the lamps therein after the conductors 11 have been properly coupled up to the mains, is placed against the ceiling in such manner that the pipe or sustaining member 7 projects through the passage 8, after which the nut 10 is applied to secure the bowl directly against the ceiling.

With the fixture of the invention all metal rings, chains, etc., may be eliminated and 30 the bowl may be installed directly against the ceiling, thus sealing the interior of the bowl against entrance of dust and dirt. Of course sustaining chains might be employed and certain advantages of the fixture retained, but with the loss of other advantages. It is unnecessary with the bowl constructed as described to provide any metallic supports for the lamps, and this is made possible by the fact that the bowl and pendent shades are either frosted or made of milk glass or the like, thereby producing a diffusion of the light to hide direct vision of the lamps and distributing the illumination. While the bottoms of the shades do not have to be 45 made of clear glass it is preferable that they should be so made. Nor is it necessary that the bowl and shades or the shades forming part of the bowl be made of frosted, or milk, or opaque glass. In fact the bowl and shades 50 may be made of any appropriate kind of glass, which may also form the bottoms of the shades.

Essential features of the invention are the formation of the bowl and shades of one 55 piece of glass and, in the simpler forms, the bowl is held flush up against the ceiling with the shades pendent and all metal parts eliminated, the sustaining member 7 which may be conveniently made of iron pipe, and the 60 nut or knob 10 which, because exposed to view, may be made of brass or some other suitable material.

What is claimed is:—

1. An electric light fixture, comprising a 65 bowl and a series of pendent shades carried

by and extending below the bowl, said shades and bowl being formed in one piece.

2. An electric light fixture, comprising a bowl having a series of pendent shades arranged marginally of and opening at the 70 upper ends into the bowl with the bottoms of the shades closed, whereby the shades may receive and support electric lamps loosely placed therein.

3. An electric light fixture, comprising a 75 bowl of light-diffusive glass, with a marginal series of dependent shades also of light diffusive glass and each having a closed bottom of clear glass.

4. An electric light fixture, comprising a 80 glass bowl with a marginal series or cluster of glass shades formed in one piece with the bowl and each with a closed bottom and opening at the top into the bowl and of a size to receive an electric incandescent lamp 85 in a substantially upright position.

5. An electric light fixture, comprising a glass bowl with a marginal series or cluster of glass shades formed in one piece with the bowl and each with a closed bottom and 90 opening at the top into the bowl and of a size to receive an electric incandescent lamp in a substantially upright position, said bowl having a central passage, and sustaining means for the bowl projecting through the 95 passage and provided at the lower end below the bowl with a knob upon which the bowl rests and by which it may be clamped with the upper edge of the bowl flush against a 100 ceiling.

6. An electric light ceiling fixture, comprising a one-piece glass bowl and cluster of shades pendent therefrom, said shades being closed at the lower ends and opening into the bowl at the upper ends, and a single 105 pendent stem fast at the upper end to a fixed support and at the lower end traversing the central portion of the bottom of the bowl and provided below the bowl with means for upholding the latter with its upper edge against 110 the ceiling.

7. An electric light fixture, comprising a one-piece bowl and cluster of pendent shades, all of glass, each shade expanding upwardly and opening into the bowl through the bottom thereof, and having a closed bottom, whereby each shade will receive and constitute the sole support for a loose electric lamp bulb.

8. In an electric light fixture, a bowl having a series of pendent shades carried thereby and formed in one piece therewith, in combination with a single support passed through an opening of the bowl, and a knob on the lower end of the support and serving 125 to hold the bowl on the latter, said support being of a length to hold the open end of the bowl against a ceiling when the knob is applied.

9. An electric light fixture comprising a 130

glass bowl with a series of pendent shades formed in one piece with the bowl and opening upwardly into the body of the bowl with the combined depth of the bowl and a shade 5 such as to loosely receive and hold an electric lamp and its socket in substantially upright position wholly within the bowl and respective shade.

10. In an electric light ceiling fixture, a bowl having a series of shades projecting 10 from and formed in one piece therewith and

said bowl having a central opening about which the shades are spaced, in combination with a single central elongated support, for the bowl, having a knob at the lower end in 15 the form of a nut, said knob holding the open end of the bowl in contact with the ceiling.

In testimony that I claim the foregoing as my own, I have hereto affixed my signature. 20

RICHARD S. GIESE.
